UNITED STATES PATENT OFFICE.

HENRY GROTHE, OF LE SUEUR CENTER, MINNESOTA.

PICTURE-HANGING DEVICE.

Application filed February 25, 1925. Serial No. 11,446.

To all whom it may concern:

Be it known that I, HENRY GROTHE, a citizen of the United States, residing at Le Sueur Center, in the county of Le Sueur and State of Minnesota, have invented certain new and useful Improvements in Picture-Hanging Devices, of which the following is a specification.

My invention relates to devices for hanging pictures, mirrors, etc., on walls and the object is to provide a simple, efficient and inexpensive device particularly adaptable for hanging pictures in frames at any desired height and in proper horizontal position.

In the accompanying drawing:

Fig. 1 is a front elevation of my device in operative position holding a picture frame in suspended position from a picture moulding on a wall.

Fig. 2 is a face view of my device alone, in enlarged scale, its sliding member being shown in section longitudinally on a vertical line.

Fig. 3 is a detail view as on line 3—3 in Fig. 2, enlarged, showing mainly the moulding engaging hook of my device.

Fig. 4 is an enlarged sectional elevation as on line 4—4 in Fig. 2.

Fig. 5 is an enlarged sectional elevation as on line 5—5 in Fig. 1 showing the method of attaching the hanger bars or arms of my device to a picture frame.

Referring to the drawing by reference numerals 10 designates the main member of my device comprising a vertically disposed bar, preferably light bar iron, the upper end of which has a hook 10^a adapted to engage a picture moulding 11 of the kind usually secured as at 12 on a wall 13 near the ceiling (not shown) the said bar preferably being long enough so that its lower end may be easily reached by a person standing on the floor.

On the bar 10 I mount a sliding member resembling a cross-head, of flat tube shape, preferably made of a single piece of sheet iron bent to form a front wall 14, rear wall 14^b, a top spacing wall 14^b and a like wall 14^c at the bottom (see Figs. 2 and 4). Walls 14^b and 14^c are provided with registering central slots 15 for insertion of the bar 10 the space within the member at each side of the bar thus forming two opposite pockets 16^b and 16^c at right and left respectively (see Fig. 2).

19 is a wire ring suitably suspended from an aperture 10^b in the lower end of the bar 10 and large enough to prevent the cross head from sliding off the bar.

17^R and 17^L are angular metal bars each with its inner end pivoted on a pin 20 fixed horizontally in member 14 near bar 10 and each of said bars extends upwardly and outwardly from its pivot. The innermost end of each bar 17 is pointed downwardly as at 17^x in Fig. 2 toward bar 10, both said points adapted to contact with the opposite sides or edges of the main bar when there is weight on the outer ends of the bars. Said outer ends have each a depending flat bar 18^R—18^L pivoted one at 21^R and the other at 21^L both said bars or arms 18 being of the same length and having each a slot 18^A adjacent its lower end for a purpose presently to be described.

In Figs. 1 and 5, 22 represents a quadrangular wooden picture frame having a glass 23 covering a picture (not shown). 24 in Fig. 5 shows the usual eye-screw of which there is one in each end of the picture frame for suspending a picture by means of wire (not shown) secured in said eye-screws and passed over a hook (not shown) on the moulding. With my device 85 these eye-screws are used by simply turning each one so its head is in a proper plane to pass slot 18^A of rod 18 over it and toward the rear face of the frame (see Fig. 5) after which the eye is turned at right angles to slot 18 and thus each bar is securely held. It will be readily understood that the weight of the picture frame pulls down on the bars or arms 18 and levers 17 causing the inner cam-like ends 17^x to press against opposite sides of bar 10 and hold the picture in proper suspended position at any desired elevation.

To raise or lower the picture the operator merely holds ring 19 with one hand to hold bar 10 steady then pushes upwardly on the picture frame with his other hand. This causes bars 18 to raise the outer ends of levers 17 as to the positions shown dotted in Fig. 2 causing cams 17^x to be swung outwardly from the bar 10. As there is then no frictional contact the picture may be raised or lowered to the desired place. As soon as the operator releases the picture frame its weight causes the cams to grasp bar 10 again, as described.

What I claim is:

1. In a picture hanging device, a main

vertically disposed bar adapted to be suspended from a fixed element, a cross member 5
slidable on said bar, vertically tilttable levers
pivotally secured in said cross member one
at each side of the main bar and adapted to
simultaneously engage opposite sides of the
bar, a depending arm pivotally secured to
the outer end portion of each lever and
means for detachably securing the lower
end of each arm to a frame.

2. The structure specified in claim 1 in
which the inner ends of said levers are each
formed with a downwardly and inwardly

directed part to frictionally engage the main
bar when the lever is pulled downwardly at 15
its outer end.

3. The structure specified in claim 1 in
which said depending arms are each provided
with an elongated aperture adjacent 20
its lower end for the purpose set forth.

4. The structure specified in claim 1 and
means secured to said main bar to prevent
the slideable parts from coming off the bar.

In testimony whereof I affix my signature.

HENRY GROTHE.
